UNITED STATES PATENT OFFICE.

ELMER O. BEARDSLEY AND WALTER F. PIPER, OF CHICAGO, ILLINOIS, ASSIGNEES TO THE BEARDSLEY & PIPER COMPANY, OF CHICAGO, ILLINOIS, A CORPORATION OF ILLINOIS.

MOLDING MACHINE.

Application filed January 25, 1922. Serial No. 531,803.

To all whom it may concern:

Be it known that we, ELMER O. BEARDSLEY and WALTER F. PIPER, both citizens of the United States, and residents of Chicago, in the county of Cook and State of Illinois, have invented certain new and useful Improvements in Molding Machines, of which the following is a full, clear, and exact description.

10 The invention relates to machines for projection sand in making moulds for founding.

One objection of the invention is to provide the rotor which carries the projector-blade with means for displacing the air in the rear of the blade. In practice, it has been found that the displacement of the air behind the projector blade causes the wads of sand to become more dense, which 20 is a desideratum in the high speed projection of sand.

Another object of the invention is to provide improved means for detachably securing the projector blade to the rotor body by 25 which the operative surface of the blade will be left free of projections.

The invention consists in the several novel features hereinafter set forth and more particularly defined by claims at the 30 conclusion hereof.

In the drawings: Fig. 1 is a section taken on line 1—1 of Fig. 2. Fig. 2 is a vertical axial section on line 2—2 of Fig. 1. Fig. 3 is a detail section of the body of the rotor. Fig. 4 is a perspective of the projector blade. Fig. 5 is a section showing the device for attaching the projector-blade to the rotor-body. Fig. 6 is a perspective of the seat for the projector blade in the rotor-body. Figs. 7, 8 and 9 are perspectives of the rotor.

The invention is exemplified in a structure comprising a horizontally swinging tabular supporting arm 6, which is usually supported as exemplified in our Patent No. 1,309,833, dated July 15, 1919, but may be supported in any suitable manner; a motor-driven shaft 7 extending through said arm; a stator or casing which is suitably and rigidly supported by a yoke 10 which is fixed to the arm 6, as more fully illustrated in said patent, and comprises an upper arcuate peripheral wall 9 with a side wall 8, a lower arcuate wall 9^a and a sand outlet 9^b; a suitably driven endless belt 11 which is

adapted to feed sand through an opening 9^c at the inner side of the casing and passes around a roller 12 which is suitably supported on the arm 6; a rotor-body which is mounted on roller-bearings 13, 14 carried by the outer end of arm 6 and secured to rotate with, and be driven by, shaft 7 by means of a driving-collar 15 which is keyed to the projecting end of said shaft and secured to the rotor-body by bolts 16, and a projector-blade 30 on the rotor-body.

The rotor-body comprises a hub 17, an outer peripheral wall 19 adjacent the casing-periphery and integral with hub 17, and a helicoidal wall 20 between the hub and said wall, commencing as at 21 at the outer end of the projector-blade and extends helicoidally to the other end of the projector-blade 30 at 22. Said blade comprises a curved deflecting portion 23 for directing the wads of sand to, and packing them against, wall 9 of the casing, and a shear-blade 24 at the inner end of the rotor-body for severing wads of sand from the stream fed to the projector by the endless-belt 11. The rotor is provided with a weight 31 to counterbalance the oppositely disposed blade and metal.

A characteristic of this construction is that the outer peripheral wall 19 and helicoidal wall 20 serve as means to displace the air from the zone of rotation of the projector-blade, whilst leaving only sufficient space for the sand to pass into the path in front of the projector. These walls 19 and 20 form air-displacing means in the zone of rotation of the blade and of progressively increasing area from the front of the blade to its back, thus forming a sand receiving space in said zone which is of progressively increasing area from the back of the blade to its front, so that the proper delivery of the sand to the rotor will not be interfered with. A desideratum is to densify the wads of sand, particularly when the projector is used at an exceptionally high speed, and by providing such air displacing means, less air accumulates in front of the projector and resultantly there is less atmospheric resistance tending to spread the sand and greater density in the wads formed between the blade and casing and projected into the flasks.

The projector blade 30 is secured to the rotor-body by an undercut rib 25 on the

blade which fits against a correspondingly undercut rib 26 on the rotor-body to form an interlock between the blade and body, and a bolt 27 which extends through the

- 8 rotor-body, is provided with a hook 28 for engaging the inner edge of the projector blade and is provided with a nut 29 which draws the hook 28 into position to secure the blade in a curved seat interlocked at 10 ribs 25, 26. This detachable connection for securing the blade on the rotor-body exemplifies one in which no drilling of holes is necessary in the curved face of the blade. In practice, the blade is formed of hard 15 metal and it has been found that when bolts are used which extend through the base of the blade, they cannot be readily made to conform truly to the outer curved face of the blade. A smooth face is desirable to 20 facilitate the deflection of the sand to the outer portion of the blade by centrifugal force. By providing the interlock 25, 26, and a hook at the lower margin, the necessity of drilling holes and fitting bolts in the base 25 of the blade is avoided.

The invention exemplifies an improved sand projector for filling flasks to form moulds in which the rotor is provided with means for displacing air behind the projector-blade to densify the wads of sand and also an improved attaching means for the projecting blade which avoids the necessity of drilling holes in its base.

30 The invention is not to be understood as restricted to the details set forth, since these may be modified within the scope of the appended claims, without departing from the spirit and scope of the invention.

35 Having thus described the invention, what we claim as new and desire to secure by Letters Patent, is:

1. In a molding machine, the combination of a suitable support, of a rotor provided with a projector blade, means for feeding sand to the blade, and air-displacing means on the rotor and in the zone of rotation of the blade.
2. In a molding machine, the combination of a suitable support, of a rotor provided with a projector-blade, a casing around the rotor, means for feeding sand to the blade, and air-displacing means on the rotor and in the zone of rotation of the blade.
3. In a molding machine, the combination of a suitable support, of a rotor provided with a projector-blade, a casing around the blade, means for feeding sand to the blade, and air-displacing means on the rotor in the zone of rotation and of progressively increasing area from the front to the rear of the blade.
4. In a molding machine, the combination of a suitable support, a rotor provided with a bed and a projector-blade on said bed, means for feeding sand to the rotor longitu-

dinally of the rotor, and air-displacing means on the rotor and in the zone of rotation of the projector blade.

5. In a molding machine, the combination of a suitable support, a rotor provided with a projector-blade, means for feeding sand to the rotor longitudinally of the rotor, and air-displacing means in the zone of rotation of the projector-blade, and extending longitudinally of the rotor to form a sand-space of progressively increasing width from the rear of the blade to its front.

6. In a molding machine, the combination of a suitable support, a rotor provided with a projector-blade, means for feeding sand to the rotor longitudinally of the rotor, and a wall on the rotor for displacing air in the zone of rotation of the projector-blade and formed to progressively increase the sand-space from the rear to the front of the blade.

7. In a molding machine, the combination of a support, a rotor comprising a body and a projector blade, the body being formed with a helicoidal wall to displace air behind from the zone of rotation of the blade, and a casing around the rotor.

8. In a molding machine, the combination of a suitable support, a rotor comprising a body and a projector-blade, the body being formed with a helicoidal and peripheral wall to displace air from the zone of rotation, and a casing around the projector.

9. In a molding machine, a ramming head comprising in combination a rotor body, a projector blade on said body, an interlocking connection between the body and the blade, and means for securing the connection to secure the projector blade on the body.

10. In a molding machine, a ramming head comprising in combination a rotor body, a projector blade on said body, an interlocking connection between the body and the blade, and means adjacent and outside of one end of the blade for securing the connection to secure the projector blade on the body.

11. In a molding machine, a ramming head comprising in combination a rotor body, a projector blade on said body, an interlocking connection between the body and the back of the blade, and means for securing the connection for securing the projector-blade on the body.

12. In a molding machine, a ramming head comprising in combination a rotor body provided with a seat, a projector blade on said seat interlocking ribs between the body and one end of the blade, and means extending through the body and holding one margin of the blade to secure the ribs in interlocking relation.

13. In a molding machine, a ramming head comprising in combination a rotor body provided with a seat, a projector blade

on said seat, interlocking ribs between the seat and one end of the blade and a bolt extending through the body and holding one margin of the blade to secure the ribs in interlocking relation.

14. In a molding machine, a ramming head comprising in combination a rotor-body provided with a seat, a curved projector-blade on said seat, interlocking ribs be-

tween the seat and the back of the blade, 10 and a bolt extending through the body and holding one margin of the blade against displacement and securing the ribs in interlocking relation.

Signed at Chicago, Illinois, this 7th day 15 of January, 1922.

ELMER O. BEARDSLEY.
WALTER F. PIPER.
